PRINTING TELEGRAPH SYSTEM

Albert H. Reiber, Evanston, and Walter J. Zener, Des Plaines, Ill., assignors to Teletype Corporation, Chicago, Ill., a corporation of Delaware

Application August 30, 1934, Serial No. 742,066

16 Claims. (Cl. 178—4.1)

This invention pertains to telegraph systems and more particularly to printing telegraph receiving circuits and apparatus.

The principal object of the invention resides in the provision of a receiving printer arranged to be non-responsive under certain conditions of operation.

An important feature of the invention consists in the provision of means to maintain mechanically the selector magnet armature of the printer in stop or marking position during non-signalling periods when it would otherwise tend to assume its spacing or starting position resulting in the recording of false signals.

Another feature of the invention resides in the provision of a centrifugally controlled means associated with the motor for preventing the operation of the printing apparatus unless the motor has attained its operating speed, and which, in cooperation with an auxiliary magnet adapted to control the action of the selector magnet, positively prevents the printing of false characters.

The present invention contemplates the provision of a single magnet selector mechanism responsive to code combinations of signalling impulses, wherein there is associated with the selector magnet a selector lever comprising an armature and an armature extension. The aforementioned and other objects of the invention are accomplished by the association with said selector magnet of an auxiliary magnet having its armature so arranged as to act, under predetermined conditions, upon the selector armature extension to hold the latter in its stop or marking position. In one form of the invention the armature of the auxiliary or anti-spin magnet (so called from the fact that it functions to prevent the selector lever, due to an open line or prolonged spacing condition, from releasing the selector cam member for continuous rotation and consequent false printing) is adapted to latch mechanically the selector lever in its stop or marking position. In another form of the invention the armature of the anti-spin magnet is provided with a spring which is so chosen as to overpower the selector lever spring, in which event, upon the simultaneous deenergization of the selector and anti-spin magnets, the armature of the latter magnet will act to maintain, due to its greater biasing effect, the selector lever in its stop or marking position.

Moreover, upon the printer motor shaft is carried a centrifugal device which functions to control a contact assembly which, in turn, serves to

control certain of the printer circuits, among which are the selector magnet and anti-spin magnet circuits, so as to render the printing apparatus effective only when the motor has attained its normal operating speed and thereby, in conjunction with the anti-spin magnet, preclude the possibility of printing false characters.

A better understanding of the invention may be had from the following description, taken in conjunction with the accompanying drawing, 10 wherein,

Fig. 1 is a fragmentary plan view of a selector mechanism of the sword-and-T-type, controlled by a neutral magnet, with portions omitted or broken away to reveal the essential operating members in which the present invention is embodied;

Fig. 2 is a sectional view taken substantially on line 2—2 of Fig. 1;

Fig. 3 is a simplified circuit diagram illustrating the application of the present invention;

Fig. 4 is a view partially in section of the centrifugal device according to the present invention;

Fig. 5 is a front elevation similar to Fig. 1 of 25 a selector mechanism showing an alternate arrangement of the present invention;

Fig. 6 is a sectional view taken on line 6—6 of Fig. 5, and

Fig. 7 is a circuit diagram showing one method 30 of delaying the release of the selector magnet until the anti-spin magnet of the present invention has been previously released.

Having reference to the accompanying drawing in which like reference characters indicate 35 similar parts throughout, the selector mechanism illustrated in Fig. 1 is similar to that which is used commercially in several standard types of printing telegraph machines. The selector mechanism disclosed is shown only in sufficient 40 detail to enable an understanding of the present invention. For a complete understanding of details not disclosed herein and which form no part of the present invention, reference may be had to Patent No. 1,745,633 to S. Morton et al., 45 which shows printing telegraph transmitting and receiving apparatus to which the present structure is particularly applicable.

This mechanism comprises a set of six (or five, depending on the code adopted) selector elements in the form of thin, flat fingers or swords 11 arranged in superimposed relation between guide plates 12. These plates are mounted on studs 13 and spaced by washers not shown. The circular rear ends 14 of the fingers 11 engage 55

corresponding sockets 15 in six thin, flat bell cranks 16, pivoted on a common shaft 17. Individual springs 18 normally hold the bell cranks 16 and selector fingers 11 in the positions shown in Figs. 1 and 5 with the pointed end 19 of the bell crank 16 in contact with a selector cam barrel 21 on shaft 22 which is driven continuously by a properly regulated motor, the driving connection between the shaft 22 and the cam barrel 21 being established through friction clutches, one of which is indicated at 20 (Fig. 2).

The cam barrel 21 is provided with a helically arranged series of cams 25, one for each of the bell cranks 16, which rotate the bell cranks 16 in succession and thus reciprocate longitudinally the corresponding series of selector fingers 11 as the cam barrel 21 is rotated. In addition to the longitudinal movement, the selector fingers 11 have a lateral swinging movement between the pair of studs 26.

The setting of any selector finger 11 either to its dotted-line or solid-line position (as indicated in Fig. 1) is determined by the selector electromagnet 27 which is mounted on a bracket 28 in the printing apparatus. The armature 29 is carried by a lever 31 which is pivoted on a shaft 32 supported in the frame of the apparatus. The unit comprising lever 31 and armature 29 is maintained, when the line circuit is closed and magnet 27 is accordingly energized, in the position shown in Fig. 1, against the action of a spring 38, the tension of which may be adjusted by an adjusting screw 39. Lever 31 terminates in a U-shaped portion 35, having downward extending arms 36 which constitute abutments which cooperate with arms 37 on the rear ends of the swords or selector fingers 11, and act to position the latter in either the dotted-line or solid-line position. That is, the distance between the depending portions 36 of lever 31 is somewhat less than the distance between each cooperating pair of lugs 37, so that when either of the portions 36 is disposed to register opposite its cooperating lugs 37, the other of the two portions 36 falls short of engagement with its cooperating lug 37. As may be seen from Fig. 1, spring 38 tends to maintain lever 31 so that one of its portions 36 registers opposite its associated lug 37 while magnet 27, upon energization, operates to maintain it so that the other of its depending portions 36 registers opposite its associated lug 37. In other words, the energization of magnet 27 causes the presentation of lever 31 in one position to cooperate with one of the abutments of the swords 11, while its deenergization causes its presentation in the other position to cooperate with the other of the pair of lugs 37.

The selector fingers 11 act through a corresponding number of T-shaped levers 41 arranged between the guide plates 12 and pivotally mounted on a stud 42, to position a set of code elements which are not shown but are exemplified by the fragment 43 and are capable of being moved into one or the other of two positions. To each element 43 is articulated one arm of T-lever 41. As indicated T-levers 41 are provided with two symmetrical and oppositely disposed extensions which coact with the end of their individual selector fingers 11 so that the T-lever 41 is rocked in conformance with the selected position of selector finger 11 to actuate in turn its associated element 43 correspondingly.

A magnet 45 supported by bracket 46 cooperates with an armature 47, the remote end of

which is notched at 48 (Fig. 2) and is located so as to receive within its notch 49 a narrow portion 49 of selector lever 31. As previously indicated, magnet 45 is herein known as the anti-spin magnet, in accordance with the present invention. Each magnet 27 and 45 has its own energization control switch, as will hereinafter appear, so that when line relay 51 (Fig. 3) receives a current condition from the signal line in accordance with the prevailing practice, magnet 27 is energized by the movement of the armature 52 which closes a circuit to energize selector magnet 27.

The anti-spin magnet 45 is energized at such times when the station is in communicative condition, while it is deenergized at other times, and because armature 47 is effective only during the deenergized condition of its magnet 45 and is ineffective during the energized condition thereof, it will restrain selector lever 31 in marking position, except when the receiving mechanism is in communicative condition.

Referring further to Figs. 1 and 2, it is noted that the selector lever 31 is provided with a projection 53 terminating in an eccentric adjustment screw 54, the function of which is to initiate through a series of levers the rotation of the selector cam barrel 21 in a manner clearly set forth in Patent No. 1,745,633. Briefly, however, for the purpose of the present disclosure, this arrangement has been partially shown in Fig. 2 wherein the adjustable screw 54 coacts with a plunger 55 carried in support 56 which actuates a small bell crank 57, pivoted at 58 in support 56, to rock a latch member 59, pivoted at 61 to support 62, mounted on an orientation plate 63. Latch 59 is normally urged by a spring 64 into locking engagement with a stop member 65 pivoted on a stud 66 secured to plate 63. Stop 65 is of U-shaped conformation, the lower arm of which cooperates with stop disc 67 to arrest the rotation of selector cam barrel 25.

In operation, upon the receipt of a spacing or start signal, the selector magnet 27 becomes deenergized and armature lever 31 is actuated by its spring 38 in a clockwise direction (as viewed in Fig. 1), thus carrying the adjusting screw 54 therewith. This movement of the selector lever 31 through screw 54 acts to move plunger 55 to rotate, in turn, bell crank 57 in a counterclockwise direction (as viewed in Fig. 2) to rock latch 59 rightwardly against the urge of spring 64 to unlatch member 59 from stop arm 65. Since the stop disc 67 is subjected to a constant torque due to its frictional connection with constantly rotating shaft 22, but is held from rotation by the stop arm 65, it will, upon the unlatching of member 59 on stop arm 65, cause stop arm 65 to rotate about stud 66 until it is free of said stop arm, whereupon the stop arm 65 will again return to its normal position by the action of a spring, not shown, into latching engagement with member 59 so that when stop disc 67 has completed one revolution it will again coact with stop arm 65 which, being restrained by latch member 59, will arrest the rotation of stop disc 67 and hence selector cam drum 21.

An alternate form of anti-spin arrangement is illustrated in Figs. 5 and 6, in which a blocking type of anti-spin device is provided for holding a selector lever 31 against actuation, instead of the latching type as shown in Figs. 1 and 3. In this embodiment the anti-spin magnet 128 is substituted for the corresponding magnet 45 of Fig. 1, the support 129 therefor being disposed as

indicated in Fig. 5. The armature 131 of anti-spin magnet 128 is pivoted at 132 and is provided at its opposite extremity with a depending pin 133 which serves, when magnet 128 is deenergized, and armature 131 is rotated clockwise by its spring 134, to block or restrain selector lever 31 in its counterclockwise position, the spring 134 being stronger and thereby adapted to overpower spring 38.

Referring now to the circuit diagram shown in Fig. 3, the broken-line square indicated generally as 71 represents the printer and the rectangle indicated generally as 72 represents the control box therefor at a subscriber's station. Electrically, the anti-spin device consists primarily of an electromagnet and centrifugally operated contacts which function to prevent the false operation of the receiving printer when the motor is first connected to the line; that is, before it has attained its normal operating speed, and also when the motor is being stopped. The centrifugal switching device shown in Fig. 4 and indicated generally as 73 in Fig. 3 consists of a rotor 74 mounted on the motor pinion 75 and a contact assembly indicated generally as 76 mounted on the base of the printer. The rotor contains a pair of weights 77 pivoted on individual pivots 78, which move away from the axis of rotation as the motor accelerates. The centrifugal or outward motion of these weights acts through arms 79 and disc 81 to compress a spring 82 and allow the contact assembly 76 under its own spring action to change its position. When the motor stops, the reverse or original condition again exists and the compression spring 82 returns the contact assembly to its right-hand position (as viewed in Fig. 3).

The contact assembly 76 consists of make-break or transfer contacts 83-84 and a make contact 85. Included also in the energizing circuit for the anti-spin magnet 45 is a contact 86 which is one of a pair of contacts controlled by a pull bar 87 in the printing apparatus, the other contact 88 of said pair is included in the energizing circuit for the circuit-breaker magnet 99 of the motor control unit indicated generally as 91.

The relation between the armatures of the selector and anti-spin magnets may be either as shown in the preferred embodiment in Figs. 1 and 2 or as in the modification shown in Figs. 5 and 6. In the preferred form the armature 47 of the anti-spin magnet acts, under certain predetermined conditions, to latch the armature lever 31 in its operated or marking position, thus preventing, upon a cessation of signalling, the release of the selector cam member 25 for continuous rotation, and consequently, the printing of false characters. A similar effect is obtained by the embodiment shown in Figs. 5 and 6, but in this instance the armature lever 31 is maintained, upon the simultaneous deenergization of both the selector and anti-spin magnets, in its marking position by reason of the fact that spring 134 for armature 131 is so chosen as to overpower the selector armature spring 38. In the circuit diagram in Fig. 3, the principle embodied in Figs. 5 and 6 has been adopted since that modification lends itself more readily to a schematic showing thereof; but it is, of course, understood that the principle embodied in Figs. 1 and 2 is equally adaptable.

Under normal conditions when a subscriber's station circuit is not connected for communication, a circuit may be traced from the ring side R (Fig. 3) of the transmission line extending from the subscriber's premises to the central office

through a condenser 95 and bell ringer 96 through contact 97 of a flash or recall key 94, over conductor 98, through contact 84 of the centrifugally controlled switching device 73, over conductor 99 to ground. This ground is also normally connected to the tip side T of the transmission line over a path traced from T through the winding of polarized relay 51, through polarized relay 101, contact 97 of recall key 94, conductor 98, contact 84 of the centrifugal switching device 73, conductor 99 to ground. As will hereinafter appear, relay 101 is operated by means of current supplied through the tip side of the line only. The circuit hereinbefore traced from the ring side R of the line through the bell ringer to ground permits the operation of this bell ringer to attract the attention of the subscriber at the station when ringing current is transmitted over the ring side R of the line from the central office. As will also appear hereinafter, the circuit from the tip side T of the line through relays 51 and 101 to ground is provided to enable the motor to be started from the central office in the event that the subscriber's station is unattended.

The operator at the subscriber's station, in response to the ringing of the bell 96, answers the call by manually closing contact 102 (commonly designated as the "answer" key), the effect of which is to establish an energizing circuit for motor control magnet 103 from source of current, through the magnet 103, over conductor 104, through contact 102 (now closed momentarily) over conductor 105 to ground. The energization of magnet 103 causes the armature 106 to pull up, thereby unlatching contact assembly 107 to close simultaneously circuit-breaker 108 and contact 109. Current then flows from source of alternating current (or direct current if preferred), through circuit-breaker contact 108, over conductor 111, through motor 112, to ground, thus starting the motor 112 into operation. At the same time, a circuit is completed from said source through circuit-breaker contact 108, over conductor 113, through rectifier 50, over conductor 105 to ground, thereby operating the rectifier 50 to produce direct current for local use.

As the motor 112 accelerates, it operates the centrifugal switching device 73 to effect, upon reaching normal speed, a change in the contact assembly 76, such that contacts 83 and 85 (formerly open) will now be closed, and contact 84 (formerly closed) will now be open. The opening of contact 84 breaks the ground circuit for magnet 101, thereby causing it to deenergize, and also breaking the bell ringer circuit over the ring side R of the line. Moreover, opening contact 84 removes ground from the tip side T of the line and connects, through the closing of contact 83, the T and R leads of the line from the central office through the subscriber's stations set. Included in this last mentioned circuit are the sending contacts 114 and the break contact 115 of the subscriber's transmitting set.

The closing of contact 85 establishes an energizing circuit for the anti-spin magnet 128 from source of current, which may be from the positive terminal of rectifier 50 (now operated), over conductor 116, through contacts 85 and 86, over conductor 117, through winding of magnet 128, over conductors 118 and 119 to opposite terminal of said source of current. Upon energization of magnet 128, its armature 131 is operated, thus removing the restraint from armature 31 of selector magnet 27 which latter magnet and armature are now free to operate in response to selective signal im-

pulses. During signal intervals the anti-spin magnet 128, being of the slow release type, remains energized over the last mentioned circuit, due to the fact that the time between signal impulses is not of sufficient duration to permit the magnet 128 to release its armature.

The subscriber's station is now in condition for transmission or reception of signals. The transmission of signals is effected, as is well known, 10 through a keyboard sending device which operates the sending contacts 114 permutably to transmit permutation code signals over the ring side R of the line. The reception of signals is effectuated upon the selective operation of relay 15 51 in accordance with received signals over the loop circuit T to R, and the corresponding selective operation of armature 52, which upon the reception of each marking impulse will establish an energizing circuit for selector magnet 27 from 20 source of current (for example, the positive terminal of rectifier 59), over armature 52, through contact 128, over conductor 124 through winding of selector magnet 27, over conductor 119 to the opposite terminal of said source of current. In- 25 cidentally, polarized magnet 101, which operates only when reversed current is applied from the tip side T of the line, will not respond to signalling current nor, of course, signalling impulses.

Assuming, again, that the station (Fig. 3) is in 30 its original unoperated condition, and that it is desired to initiate a call from the subscriber's station, the operator thereat closes the manually operable contact 121 (commonly known as the "call" key), the effect of which will be the same 35 as that just described in response to the closing contact 102.

In the event that the subscriber's station is unattended, the central office may start the unattended printer thereat, thus permitting the 40 calling subscriber to transmit a message to the unattended station. This may be done by applying battery opposite in polarity to signalling battery to the tip side T of the line at the central office, which current will operate the polar relay 45 101 at the subscriber's station. The circuit extends from the tip side T of the line through the windings of relays 51 and 101, then through contact 97, over conductor 98, through contact 84, over conductor 99 to ground, thus operating relay 101 to close its contact 122. The closing of contact 122 will complete a circuit from ground, over conductor 105, through contact 122, over conductor 134, through motor control magnet 103 to source of current as, for example, the supply 55 of alternating current. The subsequent operations, that is, the operation of motor control unit 91, motor 112, centrifugal switching device 73, and anti-spin magnet 123 will be effected in the same manner as previously described in connection 60 with the closure of contact 102.

Simultaneously, however, with the energization of relay 101 and the ensuing preparation of the receiving printer for operation, the polar relay 51 will also, as previously indicated, effect the 65 operation of its armature 52 in response to signal impulses which, for marking impulses, will close contact 123, establishing an energizing circuit during marking intervals from source of current (for example, rectifier 59), over armature 52, 70 through contact 128, over conductor 124, through selector magnet 27, over conductor 119 to opposite terminal of said source of current. In response to the operation of the selector magnet 27, the selector armature, in well-known manner, 75 will also be actuated to effect, through the se-

lector mechanism shown in Fig. 1, the setting of members 43 in accordance with the received code combination of signalling impulses. At the completion of the transmission of messages to the subscriber's station, the central operator can stop the motor at the subscriber's station at will upon the transmission thereto of a motor stop signal which, in the system according to the present disclosure, is the signal for upper case "H". Upon reception of said motor stop signal by the printing apparatus 71, a pull bar 87 is actuated in well-known manner to operate in turn the contacts 86 and 88, whereby contact 86 is opened and contact 88 is closed, momentarily. The opening of contact 86 breaks the energizing circuit for the anti- 15 spin magnet 128, thus causing its deenergization and the consequent release of armature 131 by means of spring 134. In this condition, the armature 131 restrains armature 31 so that even if signals are received by the selector magnet 27 they 20 will have no effect upon the selector mechanism, since armature 31 is constrained by armature 131 against selective operation. Thus, since the magnet 128 is deenergized upon receipt of the motor stop signal, it is manifest that the selector magnet 25 27 will promptly become ineffective, thereby preventing the printing of false characters during the retardation of the motor in stopping.

The closing of contact 88 establishes an energizing circuit for magnet 89 of the motor control 30 unit 91 from source of current (for example, the A. C. supply), through contact 109, thence through the winding of magnet 89, through contact 93 to ground. The energization of magnet 89 causes the contact assembly 107 to operate to 35 become locked in its operated position by latch 106 associated with magnet 103. Thereupon, the circuit breaker contact 103 is opened, the effect of which is to open the circuit for motor 112, thus causing the latter to stop, at the same time shutting off the alternating current supply to the rectifier 59. The release of the anti-spin magnet 128 precedes the release of the selector magnet 27 by a time period equal to the attracting time of the circuit breaker contact assembly 107 associated with magnet 89 and assures proper coaction between armatures 31 and 131, and if the preferred form shown in Figs. 1 and 2 is used, it assures proper latching of the armature 31 of the selector magnet 27 by the latch 47. The time 40 period may be varied by changing the adjustment of the upper case H contacts, the magnet 89 remaining energized over a circuit through current reducing resistance 125 so long as contacts 86 remain closed.

The retardation of the motor before stopping will cause the centrifugal switching device 73 to operate the contact assembly 76 to open contacts 83 and 85 and close contact 84, thus placing the receiving circuit in the condition shown in Fig. 3. 60

Assuming, now, that the station is in operation, means is provided comprising a manually operated emergency contact 126 to interrupt the reception of messages and to place the circuit at the receiving station in a non-operative position. 65 This is effected by closing contact 126 to establish an energizing circuit for the circuit-breaker magnet 89 of the motor control unit 91 from ground, over conductor 105, through contact 106, 70 over conductor 127, through the winding of magnet 89, through contact 109 (and subsequently resistor 125) to source of current. This operation will cause the motor control unit to function to stop the motor 112 and cut off the supply of 75

alternating current to the rectifier 50, thereby preventing the receiving printer from operating in response to received signals.

There is shown in Fig. 7 an electrical means for delaying the release of the selector magnet 27 to insure the release of the anti-spin magnet prior to the selector magnet to effect the latching of armature 47. This method consists in providing an electrostatic condenser in parallel with the selector magnet of the printer for maintaining the magnet energized until the driving motor has stopped and thus preventing, through the prior deenergization of the locking or anti-spin magnet, the printing of false characters.

As indicated diagrammatically in Fig. 7, the anti-spin magnet 45, motor 112, and rectifier 50 are connected in parallel in a circuit connected to a local source of alternating current. In this circuit is also a motor control contact or power switch 135 controlled by the printer mechanism. Connected in parallel to the direct current output of the rectifier 50 are an electrostatic condenser 136 and the selector magnet 27. Also in this circuit and in series with the selector magnet 27 is a receiving relay 137 connected to the signal line 138.

Assuming that the receiving station is in operation, the motor control contacts 135 will be closed, the motor 112 will be running and the anti-spin magnet 45 will be energized, thus attracting its armature to remove the restraint therefrom from the selector lever of the selector magnet 27. Upon the closure of contacts 135 alternating current will flow through the rectifier 50, thus generating direct current which will be supplied continuously to the condenser 136, and intermittently to selector magnet 27 in accordance with the selective oscillations of the armature of the line relay 137, in response to line signals. Now, upon receipt of the motor stop signal, the motor control contacts 135 will be opened, for example, in the manner heretofore described in connection with pull bar 87 in Fig. 3, thus cutting off the supply of alternating current from the motor 112, anti-spin magnet 45, and rectifier 50. The selector magnet 27 obviously will no longer receive current from the rectifier 50, but due to the deenergization of rectifier 50, the condenser 136 will discharge its supply of current to the selector magnet 27 for a predetermined interval of time which is controlled by the resistor 139. Thus it is seen that the condenser 136, bridged or shunted across the selector magnet, will sustain the power supply to the selector magnet 27, thereby preventing the premature release thereof before the release of the anti-spin magnet 45. Therefore, the anti-spin magnet 45, being enabled to deenergize before the selector magnet 27, will effect the release of its armature 47 to latch the selector lever 31 to prevent the false operation of the printer.

It is, of course, understood that this application is intended to cover not only the specific embodiments herein disclosed, but also such changes or modifications as come within the spirit of the invention or the scope of the following claims.

What is claimed is:

1. In a control system for printing telegraph receivers comprising a selector magnet, means effective for allowing free movement of the armature of the selector magnet during signalling periods, and means controlled by the telegraph re-

ceiver for controlling said means to cause the mechanical locking of the armature of the selector magnet.

2. In a control system for printing telegraph apparatus, receiver mechanism, a selecting magnet having an armature lever, a normally energized electromagnet having its armature normally operated to allow free movement of the armature lever of the selecting magnet, and contacts controlled by the receiver mechanism for causing the deenergization of said electromagnet to effect through the release of its armature the mechanical locking of the armature lever of the selecting magnet.

3. In a control system for printing telegraph apparatus, receiver mechanism, a selecting magnet having an armature responsive to line signals, an electromagnet normally energized during reception of line signals having an armature arranged in cooperative relationship with said first recited armature, said last recited armature having a notch effective when said last recited armature assumes one of its positions for constraining said first recited armature, and contacts controlled by the receiver mechanism for causing the deenergization of said electromagnet to effect the application of constraint to said first recited magnet.

4. A printing telegraph system comprising a line circuit, a printing telegraph receiving and transmitting mechanism connected to said line circuit, an alarm mechanism associated with said printing telegraph mechanism, means for preventing the selective operation of said printing telegraph mechanism during non-reception of line signals, motor driving means for driving said printing mechanism, means for connecting said motor to a source of power, centrifugally operated means associated with said motor for rendering said alarm mechanism non-effective, and effective simultaneously for removing the restraint of said first mentioned means on said printer mechanism.

5. A printing telegraph system comprising a transmitting and receiving mechanism, a motor for driving said mechanism, motor control means operating with said mechanism for starting and stopping said motor, anti-spin means cooperative with and adapted to control the effective operation of said mechanism, and a line circuit connected to said mechanism, a selective operation of said mechanism in response to line signals being effective to control simultaneously said anti-spin means and said motor.

6. A control system for printing telegraph receivers having a selector magnet and comprising an electromagnet energized during normal signalling periods for allowing free movement of the armature of the selecting magnet of the printer, a driving motor, and an operating circuit therefor, and an electrostatic condenser in parallel with the selector magnet of the printer effective upon the breaking of said circuit for maintaining the selector magnet energized until the driving motor has stopped and thus prevent, through the prior deenergization of said electromagnet, the printing of false characters.

7. In combination, a constantly rotating member, a member to be driven by said constantly rotating member, a frictional connection between the two members, means comprising a plurality of pivotally mounted members for locking the second mentioned member against rotation, means operative under certain operating conditions for initiating the rotation of said second

- recited member, and means operative under other operating conditions for preventing the operation of said initiating means.
8. In combination, a constantly rotating member, a member to be driven by said constantly rotating member, a frictional connection between the two members, means comprising a plurality of pivotally mounted members for locking the second recited member against rotation, means operative under certain operating conditions for initiating, through said plurality of pivotally mounted members, the rotation of said second recited member, and means operative under other operating conditions for preventing the operation of said initiating means.
9. In combination, a constantly rotating member, a member to be driven by said constantly rotating member, a frictional connection between the two members, means comprising a plurality of pivotally mounted members for locking the second recited member against rotation, means operative under certain operating conditions for initiating, through said plurality of pivotally mounted members, the rotation of said second recited member, and electromagnetic means comprising a notched armature for preventing, under predetermined conditions, the operation of said initiating means.
10. In combination, a constantly rotating member, a member to be driven by said constantly rotating member, a frictional connection between the two members, means comprising a plurality of pivotally mounted members for locking the second recited member against rotation, means operative under certain operating conditions for initiating, through said plurality of pivotally mounted members, the rotation of said second recited member, means for preventing the operation of said first recited means, and unbalanced spring means operative under other operating conditions to render said last recited means effective to prevent the operation of said initiating means.
11. In a control system for printing telegraph receivers having a selector magnet and comprising an electromagnet energized during normal signalling periods for allowing free movement of the armature of the selector magnet of the printer, a driving motor, and an operating circuit therefor including said electromagnet, and an electrostatic condenser in parallel with the selector magnet of the printer effective upon the breaking of said circuit for maintaining the selector magnet energized until the driving motor has stopped.
12. In a control system for printing telegraph receivers comprising an alternating current circuit, a rectifier and an anti-spin electromagnet connected in parallel in said circuit, operating contacts selectively controlled by the printing mechanism, and a direct current circuit derived from said rectifier including an electrostatic condenser and a selector magnet for said printing mechanism connected in parallel, said electrostatic condenser adapted upon the selective operation of said contacts for maintaining said selector magnet energized for a predetermined time to insure the prior deenergization of the anti-spin electromagnet.
13. In a control system for printing telegraph receivers, a selector magnet, an armature lever therefor, an electromagnet energized during normal signalling periods having its armature operated during said periods to allow free movement of said armature lever, contacts controlled by mechanism of the receiver for causing the deenergization of said electromagnet to effect through the release of its armature the mechanical locking of said armature lever, and an energy-storing device for maintaining the energization of said selector magnet to insure the prior deenergization of said electromagnet.
14. A printing telegraph system comprising a transmitting and receiving mechanism, a motor for driving said mechanism, motor control means operating with said mechanism for starting and stopping said motor, centrifugally operated contacts controlled by said motor, anti-spin means cooperative with and adapted to control the effective operation of said mechanism, and a line circuit connected to said mechanism and said centrifugally operated contacts, a selective operation of said mechanism in response to line signals being effective to control said anti-spin means and simultaneously, through said motor, said centrifugally operated contacts.
15. In a control system for printing telegraph receivers comprising a selector magnet, an electromagnet energized during normal signalling periods for allowing free movement of the armature of the selector magnet during signalling periods, and contacts controlled by the telegraph receiver for causing the deenergization of the electromagnet and the mechanical locking of the armature of the selector magnet.
16. In a control system for printing telegraph receivers comprising a signal responsive means, means effective for allowing free operation of said means during signalling periods, and means controlled by the telegraph receiver to render said signal responsive means ineffective.
